UNITED STATES PATENT OFFICE.

CHARLES A. PETERSON, OF CHICAGO, ILLINOIS.

REFRIGERATING DEVICE.

Application filed April 14, 1919. Serial No. 289,867.

To all whom it may concern:

Be it known that I, CHARLES A. PETERSON, a citizen of the United States, residing at Chicago, in the county of Cook and State of Illinois, have invented a certain new and useful Improvement in Refrigerating Devices, of which the following is a specification.

This invention relates to refrigerating devices and has for its object to provide a new and improved device of this description. In the ordinary house refrigerator the ice is placed in one compartment and the materials or food to be cooled in placed in another compartment. The ice gradually melts and the water thus produced is drained away without being used. One of the objects of my invention is to utilize this water formed by the melting of the ice to assist in cooling the refrigerator and the material therein. The invention is illustrated in the drawings wherein

Fig. 1 is a view in section showing one form of refrigerator embodying my invention;

Fig. 2 is a plan view of the water using device with the cover removed;

Fig. 3 is a cross section through the water using device.

Like numerals refer to like parts throughout the several figures.

Referring now to the drawings I have shown one form of refrigerator 1, containing a chamber 2 for the ice and a chamber 3 for the material to be cooled. Located in the chamber 3 or at some point where its cooling effect can be utilized in cooling chamber 3 is a water using device consisting of a tank 4, having a removable cover 5. Some means is provided for conducting the water produced by the melting of the ice in chamber 2 into the receptacle 4 as for example by means of the drip pipe 6 placed to cause the water to enter the funnel 7 connected with the cover 5. Mounted in the tank 4 is a receptacle or a liquid receiver 8. Some means is provided for automatically discharging the liquid from this liquid receiver into the receptacle at intervals so that after the liquid receiver is full or partially full of the cold water produced by the melting ice, this water will be automatically discharged into the receptacle 4.

The liquid receiver is connected with a rod 9 which is pivotally mounted in the receptacle 4 at the points 10 and 11. The re-

ceptacle or liquid receiving device 8 is arranged so as to be unbalanced when containing a predetermined amount of liquid. This is done by making it eccentric with relation to the rod 9. The portion to the right of the rod and iron as shown in Fig. 3 is made heavier so as to unbalance the other portion, and is made also to engage the wall of the tank 4 as illustrated. It will thus be seen that when a predetermined amount of water has been discharged into the liquid receiver, this unbalanced condition will cause it to tip, the rod 9 rotating about its pivotal points, and thus discharge the water. If the water is discharged the counter-weighted portion returns the liquid receiver 8 to its normal position. The tipping movement of the liquid receiver 8 is limited by the pin 8^a (see Fig. 3). The tank 4 is provided with a discharge pipe 13 which is in the form of a siphon having the end 14 bent as indicated. This discharge pipe leads to any desired point of discharge.

In Fig. 3 I have shown a sectional view of the looped portion of the discharge pipe 13. Since the ice of necessity melts slowly only a small quantity of water enters the tank 4 at one time and hence, were it not for the collecting receptacle 8, the level of the water would be only raised by very small increments, and in some instances, almost imperceptible.

In referring to Fig. 3 it will be seen that if the water from the melting ice was permitted to simply enter the tank 4 as the ice melts, the water, when it reaches the level of the lower inner face of the loop part of the discharge pipe indicated at 15 would then be raised such a small amount that it would simply leak over without filling the pipe 13, and there would be no siphon effect. Under these conditions the water in the tank 4 would not be discharged except in this small leaking manner and would become warm, and its cooling effect destroyed. By collecting the water in the receptacle 8 until a sufficient amount is collected therein, and then discharging it into the tank 4 it will be seen that when the level of the water reaches the bottom of the inner face of the bend of the discharge pipe as shown at 15 there will then be discharged into the tank at one time a sufficient quantity of water to raise the level an amount sufficient to fill the discharge pipe and cause the siphon action of said discharge

2
pipe, so as to discharge all of the water down to the level of the mouth of the part 14 of said pipe.

It will thus be seen that by this means 5 the cold water may be collected in the tank 4, its cooling effect utilized and then when 10 its cooling effect ceases or is reduced the water can then be quickly discharged so that a continued cooling effect from the 15 water due to the melting of the ice may be secured.

I have described in detail a particular 15 construction embodying the invention but it is of course evident that the parts may be varied in many particulars without departing 20 from the spirit of the invention as set forth in the claims hereto appended, and I therefore do not limit myself to the particular construction shown.

25 The use and operation of my invention are as follows:

As the ice in the refrigerator melts, the 25 cold water passes down into the receptacle or liquid receiver 8. When a sufficient amount of water collects in said receptacle 30 an unbalanced condition is produced and the receptacle is tipped to discharge the water into the tank 4. This process continues until the water in the tank reaches a predetermined level. This cold water produced 35 by the melting of the ice is thus retained in the tank 4 and assists in cooling the refrigerator. The parts may be so arranged and adjusted that when the water in the tank 40 warms up so as not to be effective in helping to cool the refrigerator this water will then be discharged through the pipe 13.

This result is secured in the construction 40 illustrated by collecting the water in the receptacle 8 and then discharging it into the tank. When the level of the water in the tank reaches approximately the lower portion 45 of the loop of the discharge pipe, that is, the point 15, and then the receptacle 8 is filled until it becomes unbalanced and tips so as to discharge this collected water into the tank, the level of the water is then raised so as to cause a siphon action which 50 discharges the water from the tank. The cold water is then again collected and when 55 the level reaches a predetermined point and the receptacle 8 discharges its water into the tank, the siphon action will again occur and the water be withdrawn from the tank.

It will thus be seen that the cold water 60 can be retained in the tank 4 any desired length of time while it is effective in cooling the refrigerator, and can then be discharged to make way for new cold water, and thus 65 the cooling effect of the cold water, due to the melting of the ice, may be utilized instead of being thrown away.

I have found that with a device of this kind much less ice is necessary to keep the 70 refrigerator cool and the temperature of the

refrigerator may also be kept lower since the water produced by the melting ice has a temperature of 32° Fahrenheit. The keeping of the temperature in the ice box lower in addition to increasing the efficiency 75 of the refrigerator and the ice therein also decreases the rapidity of the melting of the ice and again increases its efficiency, the cold water thus reacting on the ice for this purpose. 75

In view of the fact that the ice necessarily melts slowly it will be seen that if the water were allowed to collect in the tank and then to remain therein, it would be raised to such a temperature that the small 80 additions of water produced by the melting of the ice would be at once heated up by the larger body, of warmer water, and thus no proper cooling effect could be attained.

With my device, however, it will be seen 85 that the maximum cooling effect of the water can be secured.

It will further be seen that by means of this construction the water slowly produced 90 by the melting of the ice is first discharged into the receptacle 8 and is then intermittently discharged into the tank, and that the water is then intermittently discharged from the tank, the latter discharges being separated by longer intervals of time than the intermittent discharge of the water into the tank. Since the water is thus slowly produced by the melting of the ice it will be seen 95 that it is collected in a receptacle of comparatively small size when it is at its lowest 100 temperature and kept separate for a time from the remaining water of the tank, although being located inside of the tank. This increases the cooling effectiveness as it holds the water thus separate from the body of the water in the tank while the water in the water collecting device is at its lowest temperature, and it further utilizes it at this low temperature to cool the air above the body of water in the tank 4, 105 this cooling effect being produced while the water is collecting and between the intermediate discharges of the water into the main body of water in the tank 4. The tank 4 is made of some suitable heat conducting 110 material, such as metal. 115

I claim:—

1. A refrigerating device comprising a receptacle, an ice chamber in said receptacle 120 for containing the ice to be used for cooling purposes, a cooling chamber in the receptacle, a tank beneath said ice chamber and located in said cooling chamber, said tank having all its sides exposed so as to act as cooling surfaces for said cooling chamber, a communication from the bottom of said ice chamber to said tank through which the water produced by the gradual melting of the ice passes into said tank, a liquid receiver 125 movably mounted in said tank into 130

- which said water is received, said liquid receiver being comparatively small so that the small quantity of water which it holds will remain at a comparatively low temperature 5 so as to act in cooling the cooling chamber, means for intermittently and automatically discharging the water from said liquid receiver into said tank where it is held for a predetermined time to also act to cool said 10 cooling chamber, and means for automatically and intermittently discharging the accumulated water from said tank after the cooling effect thereof has been utilized to cool said cooling chamber.
- 15 2. A refrigerating device comprising a receptacle, an ice chamber in said receptacle for containing the ice to be used for cooling purposes, a cooling chamber in said recepta-

cle, a tank associated with said cooling chamber and arranged to receive the water produced by the gradual melting of the ice so as to utilize said water to assist in cooling the cooling chamber, a liquid receiver mounted in said tank in an unbalanced condition adapted to receive said water, said liquid receiver arranged so that when a predetermined amount of water enters it, it will be automatically tipped to discharge the water therefrom into said tank, and means for automatically and intermittently discharging water from said tank at predetermined intervals.

In testimony whereof, I affix my signature this 3rd day of April 1919.

CHARLES A. PETERSON.
